UNITED STATES PATENT OFFICE.

CHARLES D. YOUNG, OF ALTOONA, PENNSYLVANIA.

SUPERHEATER.

1,073,205.

Specification of Letters Patent. Patented Sept. 16, 1913.

Application filed February 3, 1912. Serial No. 675,371.

To all whom it may concern:

Be it known that I, CHARLES D. YOUNG, a citizen of the United States, residing at Altoona, Pennsylvania, have invented certain new and useful Improvements in Superheaters, of which the following is a specification.

The invention relates to superheaters and is particularly applicable to locomotive superheaters. It has for its primary objects; the provision of a superheater readily applicable to the ordinary type of locomotive and having an improved means for connecting the headers and the tubes; the provision of a superheater wherein the parts may be readily and conveniently assembled and disassembled; and in general the provision of a simplified and improved form of construction having a maximum degree of durability and efficiency. One embodiment of the invention is illustrated in the accompanying drawings, wherein:

Figure 1 is a longitudinal vertical section through the front end of a locomotive boiler provided with the improved superheater; Fig. 2 is a two-part view at the front end of the smoke box of the locomotive looking to the rear, the right hand portion of the figure being in section through the smoke box in front of the superheater, and the left hand portion of the figure being in section on the line II—II of Fig. 1 with the superheater tubes removed from the fire tubes; and Fig. 3 is a two-part view looking downward, the upper half of the view being a plan view, and the lower half of the view being a horizontal section along the line III—III of Fig. 2.

Referring first to the general arrangement of parts as shown in Figs. 1, 2 and 3; 1 is the smoke box of the locomotive; 2 are the fire tubes opening into such smoke box; 3 is the dry or outlet pipe leading from the steam dome of the locomotive and lying in 45 the steam space above the fire tubes; 4 is the header casting divided by the partition 5 to the header chambers 6 and 7; 8, 9, 10 and 11 are coils of superheater tubes, each one of which has one of its front ends communicating with the header chamber 6; and the other of its ends communicating with the header chamber 7; and 12 is one of the pipes leading from the header chamber 7 to the steam chest of the locomotive, only one 55 of such pipes being shown in Figs. 1 and 2, but another pipe being provided on the

other side corresponding in arrangement and construction to the pipe shown. Only the fire tubes carrying superheater tubes are illustrated, but it will be understood that the boiler has the usual number of other fire tubes.

The bottoms of the header chambers 6 and 7 are provided with the series of openings 13 and 14 as indicated in Fig. 3, and each pair of these openings 13 and 14 is covered by a header plate 15, which extends across the bottom of both chambers as indicated in Fig. 1. In the particular construction illustrated there are eight of these closure plates. 70 Each end of each cover plate is provided with four tube openings (Fig. 3), so that each plate carries the ends of the four superheater tubes 8, 9, 10 and 11, lying immediately below such plate in the four fire tubes (Fig. 2). These four superheater tubes lying immediately beneath each closure plate, may be regarded as a set, and it will be apparent that any one of the eight sets of superheater tubes may be removed independently by detaching the closure plate thereabove from the header casting, and moving the set endwise out of the fire tubes.

The bottoms of the chambers 6 and 7 are provided with ribs 16, and the edges of the 85 closure plates 15 are secured to these ribs by means of the studs 17 (Figs. 2 and 3). The closure plates are also secured by other studs 18, which studs are threaded into bosses 19 (Figs. 1 and 3), which bosses are provided upon the upper face of the bottom wall of the headers in order to give additional metal and thus permit longer studs to be used. It will be seen by reference to Fig. 3 that each of the diamond shaped openings 13, 90 14 is surrounded by eight bolts 17 and 18 symmetrically arranged around the opening, so that sufficient holding power for the plate and a tight joint is insured. In order to give access to the ends of the superheater tubes which are expanded into the closure plates 15, openings are provided in top wall of the casting opposite each opening 13, 14 in the bottom of the casting, and these openings are closed by the removable plugs 20. 100 This provides a means whereby any particular tube may be tightened or cut out and replaced without removing the closure plate 15 carrying such tube. The removable cover plates 21 immediately above the headers 110 give access to the top of the headers without removing such headers from the boiler.

It will be noted that these cover plates are not subject to any boiler pressure. The arrangement whereby the ends of the tubes may be tightened is particularly advantageous as the superheater tubes in the upper fire tubes are not removable without removing the superheater therebeneath in the same row.

In operation, the steam from the dome 10 passes through the dry pipe 3 and into the header chamber 6. From this point it passes through the various superheater coils 8, 9, 10 and 11, and into the header chamber 7 from which point it is conducted to the steam 15 chests of the locomotive by means of the pipes 12.

It will be understood that the construction as shown and described is merely illustrative of the invention and that various 20 changes in matter of detail might be made without departing from the spirit of the invention. The header casting is shown as located above the fire tubes 2, but it will be understood that the invention is not limited 25 to this particular location of the header casting, and that the terms top and bottom as used with reference to the walls of this header are used generically to mean those walls which are remote from and adjacent 30 to the fire tubes respectively. Various means other than the ones shown for securing the wrought metal closure plates 15 to the header casting, might obviously be used, although the construction shown and described is the 35 preferred one.

Having thus described my invention and illustrated its use, what I claim as new and desire to secure by Letters Patent, is the following:

40 1. The combination with a boiler provided with a plurality of sets of fire tubes and a smoke box at its front end, of a header casting having a longitudinal partition dividing the casting into two header chambers, and 45 having in the bottom of each chamber a series of openings and in the top of each chamber another series of openings opposite

the openings in the bottom; a series of closure plates each of which extends across a bottom opening in both chambers and lies 50 opposite a set of fire tubes; superheater tubes in the said fire tubes each having one end expanded into one of said closure plates and opening into one of the said bottom openings in one header chamber and having the 55 other end expanded into the same closure plate but opening into one of the bottom openings in the other header chamber whereby each closure plate carries both ends of the plurality of superheater tubes lying in 60 the set of fire tubes opposite such closure plate; an inlet to one header chamber; an outlet from the other header chamber; removable closures for the said openings in the tops of the header chambers, whereby the 65 ends of the superheater tubes in the closure plates are accessible through such openings; and a removable plate in the smoke box wall opposite the said removable closures.

2. The combination with a boiler having 70 a smoke box at its end and a plurality of fire tubes; of a header in the smoke box extending transversely of the ends of the fire tubes and divided into two chambers; superheater tubes in the fire tubes each having one end 75 expanded into the bottom of one chamber and the other end expanded into the bottom of the other chamber, the said chambers having openings in their walls opposite the said expanded tube ends and the said smoke box having an opening in its wall opposite 80 said opening in the chambers; removable closure means for the said openings in the walls of the headers; and removable closure means for the said opening in the wall of the 85 smoke box.

In testimony whereof I have hereunto signed my name in the presence of the subscribed witnesses.

CHARLES D. YOUNG.
